UNITED STATES PATENT OFFICE.

FRANK A. MAGEE, OF CHELSEA, AND ANDREW GARBUZZ, OF BOSTON,
ASSIGNORS TO THE MAGEE FURNACE COMPANY, OF BOSTON, MASSA-
CHUSETTS.

DESIGN FOR A HEATING-STOVE.

SPECIFICATION forming part of Design No. 17,802, dated October 18, 1867.

Application filed April 1, 1867. Serial No. 233,338. Term of patent 14 years.

To all whom it may concern:

Be it known that we, FRANK A. MAGEE, of Chelsea, and ANDREW GARBUZZ, of Boston, both in the county of Suffolk and State of Massachusetts, both citizens of the United States, have invented and produced a new and original Design for Heating-Stoves, of which the following is a full, clear, and exact description, reference being had to the accompanying photographs, forming a part of this specification, in explaining its nature.

The invention relates to the design for a heating-stove having the particular ornamentation, shape, and configuration hereinafter specified.

The photograph upon Sheet 1 is a front view of the stove, and the photograph upon Sheet 2 is a side elevation.

The stove has a double-domed top, A, a cylindrical barrel or body, B, and a base-section, C, and the outlines of these parts and the proportions of each and the relation which they bear to each other are well represented in the photographs.

The top A has the polished edge a, from which rises the main dome a', and from this main dome rises concentrically a smaller dome, a''. The main dome bears at its front, preferably, an ornamental name-plate, which is curved to conform to the outline of the dome. This takes not quite one-third of the surface of the dome and leaves room for two other panels, (one on each side,) one of which is represented in the photograph on Sheet 2 at a³. The plate or panel is richly ornamented with a representation of fuchsia leaves and blossoms, and each panel is also rounded to the outline of the dome. Between these panels are ornamented sections a⁴ of the dome, which are shown in the photographs on Sheet 2.

The barrel or main section B of the stove is cylindrical in form, and is of sheet metal relieved by bars and beads struck up therefrom. b is the combustion-chamber door, and b' the door-frame. These are well shown in the photograph on Sheet 1. The design is arabesque in nature, and its essential features are the curved lines running from one side of the door and forming the boundaries or borders of open

spaces having the same irregular shape. The 50 frame or casing of the door is more renaissance than arabesque, and its nature is well represented in the photograph on Sheet 1. It comprises a series of leaf-scrolls extending at the bottom from a head or central figure about the 55 corners and at the top from a tile set in the frame downward about the corners. The upper edge of the frame extends upwardly at the center and is curved, and the lower portion of the frame extends downwardly at the center and is also 60 curved. The side rail, D, is circular in plan and has a curved outer edge, does not extend over the front of the base, and is supported at each front end by brackets d, which extend down to the posts d' at each front corner of 65 the base. Each bracket has a rosette at the end of the rail, and has a section ornamented with diverging lines or shell-work which extends toward the stove, and the foot of which also has curved lines brought together at the 70 foot and opening outward at their upper end into small scrolls.

The base has the posts d', above referred to, at each corner, which have a spherical top, an upper base-plate, e, which is richly ornamented, the front corner-posts, c', which are regularly curved and have horizontal bead-work in two groups, the front ash-pit door, c'', the hearth-plate c', and the side panels, c'. The ash-pit door c'' has line-work and figures 80 of arabesque pattern, which are well shown in the photograph on Sheet 1. One of the side panels, c', is well represented in the photograph on Sheet 2, and may be styled "renaissance," in nature.

The flue-box E extends from the hearth-plate upward to the back of the stove. It is in part continuous, rounded at the back, and having ornamental vertical border-lines e, between which and the stove there is the open-work e', (see photographs on Sheet 2,) which may also be said to belong to the arabesque school.

Having thus fully described our invention, we claim and desire to secure by Letters Pat- 95 ent of the United States—

1. In a design for a heating-stove, the front or combustion-chamber door having an ara-

besque pattern formed by curved lines running from one side of the door and forming the patterns or borders of open spaces, as illustrated and described.

5. 2. In a design for a heating stove, the frame of the combustion-chamber door, having a curved upper edge, a curved lower edge, and ornamental scroll-work extending from each upper corner inward, and scroll-work extending from the head in the lower margin to and about the corners of said frame, as illustrated and described.

3. In a design for a heating-stove, the stove-top comprising a rounded lower dome orna-

15. 15. mented with long panels of fuchsia leaves and flowers, and surmounted by a smaller dome arranged concentrically over or on the top of the lower dome, and having a series of curved lines or figures, as illustrated and described.

20. 4. In a design for a heating-stove, a long narrow panel ornamented with a representation of fuchsia leaves and flowers, as illustrated and described.

25. 5. In a design for a heating-stove, a door having vertical bars provided with an arabesque line figure in vertical and horizontal lines, as illustrated and described.

30. 6. In a design for a heating-stove, a door plate or panel having a series of straight arabesque figures separated from each other, and each of which comprises a series of curved lines forming circles or figures approaching circular form, one above the other, and connected with each other by intermediate orna-

mental lines having a curved extension from each end, as illustrated and described.

7. In a design for a heating-stove, the side panels, *c*⁴, having a central circular rosette which is surrounded by a border of arabesque pattern interwoven or joined at their corners, 40 and the side sections of which are of the same pattern, but reversely arranged, and comprise rich or heavy scroll-work, with a large central oak-leaf-shaped figure, as illustrated and de-45 scribed.

8. In a design for a heating-stove, the side panels, *c*⁴, ornamented with renaissance design, as illustrated and described.

9. In a design for a heating-stove, a flue-box, 50 *E*, rounded upon its back and having open-work sides of arabesque pattern, as illustrated and described.

10. The design for a heating-stove, consisting of a base having a straight front section, rounded corners, and curved sides and back, 55 a circular plain finished body of the same size throughout, rising from the base, an ornamented door-frame upon the front of the body and its door, and a top section comprising a large dome surmounted by a smaller dome, 60 the prevailing ornamentation of the stove being arabesque and renaissance, as illustrated and described.
